UNITED STATES PATENT OFFICE.

MARVIN L. VAN KEUREN, OF SYRACUSE, NEW YORK, ASSIGNOR TO INTERTYPE CORPORATION, OF BROOKLYN, NEW YORK, A CORPORATION OF NEW YORK.

TYPOGRAPHICAL MACHINE.

Application filed March 20, 1922. Serial No. 545,171.

To all whom it may concern:

Be it known that I, MARVIN L. VAN KEUREN, a citizen of the United States, residing at Syracuse, in the county of Onondaga and State of New York, have invented new and useful Improvements in Typographical Machines, of which the following is a specification.

The present invention relates to typographical machines and more particularly to those of the line casting type as shown and described in Letters Patent No. 436,532, granted September 16, 1890, wherein matrices released from a magazine are assembled in a so-called assembling elevator and the line so assembled is transferred to a so-called first elevator which positions the line in front of a mold to enable a type bar or slug to be cast therefrom.

In the development of machines of this class matrices each bearing a single character were first used but later matrices each bearing two characters located at different levels theron came in to use and the ma-

chines were provided with means for assembling such matrices either at the usual or lower level or at an upper or auxiliary level and for presenting the matrices to the mold at either the lower or upper level to enable

a cast to be made from either the upper or lower matrix characters, as desired. Further developments of such machines were made to accommodate matrices having large face characters, which characters frequently

extended into or over the fields previously occupied by the upper and lower characters of the previously used two-letter matrices, these large character matrices being assembled at the usual or lower level, and means

was provided for positioning these large character matrices at an auxiliary level relatively to the mold, in order to enable the type metal from the mold to properly reach all portions of such characters. The means

thus provided included, amongst other parts, a so-called filler-piece, which, when in operative position, functioned to arrest the movement of the first elevator when it reached that point in its descent at which the large

character matrices occupied the auxiliary position, such filler-piece also functioning to control a so-called "vise automatic"

which latter served to stop the machine in the event that the matrices were not properly positioned relatively to the mold, the vise 55 automatic being shown and described in the patent hereinbefore referred to.

However, in using machines constructed to assemble the ordinary matrices at either of two levels and also means for arresting 60 the movement of the first elevator, when it reaches an auxiliary position, to enable casts to be made from such large character matrices, no provision was made to prevent assembling matrices at the upper level, while 65 the filler-piece was set to arrest the first elevator at the auxiliary position, and if matrices so assembled were brought to the mold under such conditions, damage to the matrices and probably to the machine would 70 result, due to the fact that the matrices then would not register with the mold, and furthermore, should the operation of the machine continue, molten metal from the mold would squirt past the improperly positioned 75 matrices.

The primary object of the present invention is to provide means which will prevent improper presentation of the matrices to the mold, and more particularly will either 80 prevent assembling of matrices at the upper level in the assembling elevator, unless the casting mechanism is properly set to receive matrices so assembled or will prevent positioning of the assembled matrices at the 85 auxiliary level relatively to the casting mechanism unless the assembling means is set to properly assemble the matrices therefor, or both; and where a filler-piece or equivalent means is employed to arrest the 90 movement of the first elevator at an auxiliary level, the safety or controlling means will prevent assembling of the matrices at the upper level while the filler-piece occupies a position to arrest the first elevator 95 at the auxiliary level, or will prevent setting of the filler-piece to arrest the first elevator at the auxiliary level while the assembling means is set to assemble matrices at the upper level, or will do both.

To these and other ends, the invention consists in certain improvements and combinations and arrangements of parts, all as will be hereinafter more fully described, the fea-

tures of novelty being pointed out particularly in the claims at the end of the specification.

In the accompanying drawing:—

5 Figure 1 is a top plan view of the assembling and first elevators and related parts of a machine of the linotype class, equipped with safety or controlling means constructed in accordance with the present invention;

10 Figure 2 is a front elevation of the structure shown in Figure 1;

Figure 3 represents, on an enlarged scale and in vertical section, the first elevator and vise automatic and the casting mechanism, 15 illustrating the manner in which large character matrices assembled at the usual or lower level are positioned at the upper or auxiliary level in front of the mold; and

Figure 4 represents a transverse section 20 through the assembling elevator on the line 4—4, Figure 1, and looking toward the right in that figure.

Similar parts are designated by the same reference characters in the several views.

25 The present invention is applicable generally to typographical machines wherein matrices may be assembled at either of two levels and positioned at either of two levels in front of a mold adapted to cast a slug or 30 type bar therefrom. The invention is particularly applicable to machines of the well known linotype class and it is shown so applied in the present instance. It is to be understood, however, that the invention is not 35 restricted to the precise construction shown, as equivalent constructions are contemplated and these will be included within the scope of the claims.

In the construction shown, 1 represents 40 the so-called assembling elevator which may correspond substantially in its construction and mode of operation to assembling elevators generally used in machines of the linotype class. This assembling elevator embodies a channel 2 to receive matrices M and 45 also spacers S, as they are delivered from the magazine or space box to compose a line. The matrices are provided with lugs or ears 50 on their upper and lower corners to support them within the assembling elevator, and where these matrices each bear two type characters located thereon at different levels, means is provided by which these matrices may be assembled at either the ordinary or 55 lower level to bring the upper type character into use, or they may be assembled at an upper level to bring the lower type character thereon into use. In the present instance, the assembling elevator is provided 60 with a duplex rail 3 which is shiftable into and out of the matrix channel of the elevator, this rail being retracted when the matrices are assembled at the usual or lower level, but being adjustable to project into the 65 matrix channel and thus serving to provide

a support for the matrices when the latter are assembled at the upper level. This shiftable rail may be adjusted in different ways, it being shown in the present instance as provided with handles 5 and 6 by which it may 70 be set manually, these handles being mounted on a rock shaft 7 which is shiftable with the rail or the main portion thereof.

The line of matrices, when complete, is usually elevated by upward movement of the 75 assembling elevator, then transferred from the latter, through the transfer channel 1^a, to the jaws of the so-called first elevator 8 which functions to present the line of matrices to the mold, preparatory to the making of a cast therefrom. The jaws 8^a of the first elevator, in machines adapted to handle two-letter matrices or matrices assembled at two different levels, are provided with rails 9 to support the matrices when the latter are 80 assembled at the usual or lower level, and a supplemental rail 10 to support the matrices when assembled at the upper level, and in handling such matrices the first elevator must descend to its full extent, in order to 85 properly position the matrices to the mold, irrespective of whether the matrices are assembled at the lower or the upper level. Usually, the face of the body of the mold 11 is formed with upper and lower grooves 85 12 and 13 to receive the ears or lugs on the lower corners of the matrices, when the latter are assembled at the upper and lower levels respectively, the lower or upper characters on the matrices being thereby brought 100 into register with the slot or cavity in the mold.

For adapting machines of this class to large character matrices and particularly those in which the type character was extended so as to overlap partially or wholly the field occupied by both characters on the two-letter matrices, means has been provided for stopping the first elevator in an auxiliary position or a position above that which it occupies when the two-letter matrices are in use, the purpose being to position the extended character or characters so that the molten type metal from the mold may better reach and distribute itself over the 110 extended area of the character. The means usually employed for stopping the first elevator in its auxiliary position comprises a so-called filler-piece 14 which is arranged to be interposed between the top of the vise frame 15 and the under side of the cap 16 of the first elevator or in a position to be engaged by a set screw or adjustable stop 17 carried by the cap of the first elevator. As shown, the filler piece is fixed at one end to a shaft 18, the latter being rotatable in a suitable bearing 19 fixed to the top of the vise frame 15 and provided with a handle 20 by which the shaft 18 may be rotated to swing the filler-piece 14 either 130

into a position beneath the cap of the vise frame, this being the operative position of the filler-piece, or to swing the latter into an inoperative position so that the first elevator may descend to its full extent. A so-called vise automatic has been commonly used in machines of this class to stop the machine in the event that the line of matrices is not properly positioned relatively to the mold, the vise automatic including a vertically movable bar 21, the upper end 22 of which is arranged to be engaged and pressed downwardly by the cap 16 of the first elevator or by a set screw or adjustable stop 23 carried by the cap, the bar 21 being depressed sufficiently to avoid stopping of the machine when the first elevator descends to the proper extent, but causing stopping of the machine if the bar 21 is not depressed or is not sufficiently depressed by the descent of the first elevator. To insure correct operation of the vise automatic when the filler piece 14 is set in position to arrest the first elevator at the auxiliary level, an arm or extension 24 is attached to the filler-piece, this extension having the same thickness as the body of the filler-piece, and this extension, when the filler-piece is in operative position, is interposed between the upper end of the rod 21 of the vise automatic and the stop 23 so that the vise automatic will be correctly operated to avoid stopping of the machine, provided the first elevator descends fully to the auxiliary level. It is to be understood that when the filler piece 14 is swung into an inoperative position to permit descent of the first elevator to its normal or lowest level, the extension 24 is removed from operative relation with the upper end 22 of the vise automatic and the latter will then function with respect to the operation of the first elevator at its normal or lowest level.

If it were attempted to assemble the ordinary two-letter matrices at the upper level and to make a cast from matrices so assembled while the filler-piece is in position to arrest the first elevator at the auxiliary level, damage to the matrices and probably to the machine would result, because these matrices would be received on the rail 10 in the first elevator, and hence they would not register with the face of the mold. According to the present invention, means is provided which prevents assembling of matrices in the assembling elevator at the upper level, unless the filler-piece or equivalent means for causing the first elevator to stop at the auxiliary level is rendered inoperative so that the first elevator will descend to its full extent, or prevents setting of the filler-piece in operative position while the assembling means is set to assemble matrices at the upper level, or for mutually controlling the setting of the assembling means and the

filler-piece or its equivalent. Preferably and as shown, a connection is provided between the filler-piece and the upper level assembling rail in the assembling elevator, which means prevents this rail from being set to assemble matrices at the upper level until the filler-piece has been moved into inoperative position, and also prevents setting of the filler piece in operative position to arrest the first elevator at its auxiliary position unless the upper level assembling rail is set for the assembling of matrices at the lower level. As shown, the shaft 7 which is movable with the upper level assembling rail 3 or the main part thereof, has an arm 25 which is fixed thereon, and a dog 26 is provided, this dog being preferably pivoted at 27 to an adjacent stationary part of the machine and provided with a part 28 which is movable, by the pivotal movements of the dog 26 into and out of the path of the arm 25. By this arrangement, when the dog 26 is swung toward the right, incident to the setting of the filler piece in operative position, into the position shown in Figure 90 2, the part 28 of the dog will assume a position in the path of the arm 25, (assuming that the rail 3 is retracted to cause assembling of matrices at the lower level) and then the rail 3 can not be shifted into a position for the assembling of matrices at the upper level but the dog 26 can not be swung into this position if the rail 3 is in operative position for assembling of matrices at the upper level, as such movement of the dog would be blocked by the arm 25 which would then be in its path; and when the dog 26 is swung toward the left in Figure 2 to set the filler-piece in inoperative position, the part 28 of the dog will be withdrawn from the path of the arm 25 and the rail 3 can then be shifted into a position for the assembling of matrices at the upper level. The position of the dog 26 is determined automatically according to the position occupied by the filler piece 14. In the construction shown, a reciprocating bar 29 is attached at one end, as by the pivot 30, to the dog 26, the bar being shiftable endwise in a groove 31 which may be formed in the top of the vise cap 15 and the opposite end 32 of the bar extends through an opening in the bearing 19 and bears against the shaft 18 under the action of a tension spring 33. The shaft 18 at this point is flattened or recessed, as at 34, so that when the filler piece is in inoperative position, the end 32 of the bar 29 will engage the recessed or flattened portion of the shaft and the bar acting under the influence of the spring 33 will shift the dog 26 toward the left in Figure 2 and thus withdraw the portion 28 thereof from the path of the arm 25. The rail 3 can then be shifted for the assembling of matrices at the upper level. When, how-

ever, the filler-piece is moved into operative position, the unrecessed portion of the shaft 18 will bear on the end 32 of the bar and the latter will be forced toward the right, 5 bringing the dog 26 into a position where its portion 28 is in the path of the arm 25 and thereby blocks this arm from movement, (assuming the rail 3 is retracted to cause assembling of matrices at the lower level) 10 in consequence of which the rail 3 will be locked against movement in a direction to cause assembling of matrices at the upper level; but if the rail 3 is set for the assembling of matrices at the upper level at the 15 time the filler piece is to be set in operation, the arm 25 will block and prevent movement of the dog 26 until the rail 3 has been retracted. The positions of the controlling bar are assumed automatically in accordance with the movements of the shaft 18, the dog 26, in the present instance, being moved positively when the filler piece is moved toward operative position and retracted by the spring 33 when the filler piece 20 is moved into inoperative position, thus insuring proper correlation of the settings of the rail 3 and the filler-piece.

The pin 30 which normally connects the control bar 29 operatively with the dog 26, 30 is preferably tapered or pointed at its forward end, as shown, thus enabling the bar 29 to automatically detach from the dog 26 when the vise frame 15, by which the bar 29 is carried, is unlocked and swung forward, and causing the operative connection between the bar 29 and dog 26 to be automatically re-established when the vise frame is returned to its normal or usual operative position.

40 By the construction described, it will be understood that the setting of the assembling means for the assembling of matrices and spacers at either a lower or an upper level is governed according to the setting 45 of the first elevator which is capable of presenting assembled matrices to the casting mechanism, either at a lower or normal level or at an auxiliary level; and it will also be understood that the setting of the 50 first elevator to present assembled matrices to the casting mechanism, either at the normal or at an auxiliary level is governed according to the setting of the assembling means. In other words, the inter-control 55 is provided between the assembling means and the means which presents the assembled matrices to the casting mechanism. Obviously, the safety device could be constructed so that only the setting of the assembling 60 means is governed according to the setting of the first elevator, and it will also be obvious that the device could be so constructed that only the setting of the first elevator would be controlled according to the setting 65 of the assembling means. An inter-

control as shown, however, is generally preferred as neither the assembling means nor the means which presents the matrices to the casting mechanism can be set, except in accordance with one another, and hence 70 in the proper correlation in the operation of these parts of the machine is insured.

I claim as my invention:

1. In a typographical machine of the class embodying means capable of being set to cause assembling of matrices at relatively different levels, and means capable of being set to present assembled matrices at relatively different levels to the casting mechanism, a safety device governed by the setting of one of said means to control the setting of the other means.

2. In a typographical machine of the class embodying means capable of being set to cause assembling of matrices at relatively different levels, and means capable of being set to present assembled matrices at relatively different levels to the casting mechanism, an inter-control between said means to govern the setting of each of said means in accordance with the setting of the other means.

3. In a typographical machine of the class embodying means capable of being set to cause assembling of matrices at relatively different levels, and means capable of being set to present assembled matrices at relatively different levels to the casting mechanism, a safety device governed mutually by the setting of each of said means to correlate the operations thereof.

4. In a typographical machine embodying means capable of assembling matrices at different levels and means capable of presenting lines of matrices to the mold at different levels, means to prevent the assembling of matrices except in accordance with the positioning of the means which presents the matrices to the mold.

5. In a typographical machine embodying matrix-assembling means capable of assembling matrices at different levels, and an elevator provided with means for controlling the level at which it presents the line of matrices to the mold, means, controlled according to the level at which the elevator positions the matrices to the mold for preventing assembling of the matrices except in accordance therewith.

6. In a typographical machine embodying matrix and spacer assembling means and a device for presenting assembled matrices to the mold, a safety device operative to prevent assembling of matrices and spacers except in correlation with the device which presents the matrices and spacers to the mold.

7. In a typographical machine, the combination with an assembling device capable of being set to assemble matrices at relatively different levels and a device capable of be-

ing set to present assembled matrices at relatively different levels to the mold, of means governed by the setting of one of said devices to control the setting of the other device vice.

8. In a typographical machine embodying a device capable of being set to assemble matrices in relatively different ways and a device capable of being set to present assembled matrices to the casting mechanism in relatively different ways, a safety device governed by the setting of said matrix presenting device to govern the setting of the matrix assembling device.
9. In a typographical machine embodying assembling mechanism having means for setting it to assemble matrices at either an upper or a lower level and a first elevator having means for setting it to present assembled matrices to the casting mechanism at either a normal or an auxiliary level, a safety device operative to prevent setting of the assembling mechanism to assemble matrices at the upper level while the first elevator is set to present matrices to the mold at an auxiliary level.
10. In a typographical machine embodying an assembling mechanism having means capable of being set to assemble matrices at a lower or an upper level and a device having means capable of being set to cause such means to present assembled matrices to the casting mechanism at either a normal or an auxiliary level, a safety device governed in

accordance with the setting of said matrix presenting device and operative to prevent setting of the assembling mechanism to assemble matrices at the upper level while the matrix presenting means is set to present matrices at the auxiliary level.

11. In a typographical machine embodying means capable of being set to assemble matrices at either an upper or a lower level, and means capable of being set to present matrices to the casting mechanism at either a normal or an auxiliary level, a safety device governed by the setting of the assembling means to prevent setting of the matrix presenting means to present matrices to the casting mechanism at the auxiliary level while the assembling means is set to assemble matrices at the upper level.

12. In a typographical machine embodying means capable of being set to cause assembling of matrices at relatively different levels, and means capable of being set to present matrices at relatively different levels to the casting mechanism, a safety intercontrol embodying a member mutually controlled by the setting devices of the respective means to correlate the operation thereof.

In testimony whereof I have hereunto set my hand in presence of two subscribing witnesses.
